JOHN H. FRENCH, OF ALBANY, NEW YORK.

Letters Patent No. 85,376, dated December 29, 1868.

MACHINE FOR RULING SCHOOL-SLATES.

The Schedule referred to in these Letters Patent and making part of the same.

To all whom it may concern:

Be it known that I, JOHN H. FRENCH, of Albany, in the county of Albany, and State of New York, have invented a new and improved School-Slate-Ruling Machine; and I do hereby declare that the following is a full, clear, and exact description thereof, which will enable others skilled in the art to make and use the same, reference being had to the accompanying drawing, forming part of this specification, in which—

Figure 1 represents a plan or top view of my improved school-slate-ruling machine.

Figures 2 and 3 are plan views of the same, showing it in different positions.

Figure 4 is a vertical longitudinal section of the same, taken on the plane of the line $x-x$, fig. 2.

Figure 5 is a vertical transverse section of the same, taken on the plane of the line $y-y$, fig. 1.

Similar letters of reference indicate corresponding parts.

This invention relates to a new machine for ruling school-slates, of that class in which the lines are formed by scratching the surface of the slate with a pointed or sharp instrument.

The invention consists in the arrangement of the devices for adjusting the slate and the tool-heads so that lines can be ruled longitudinally, transversely, or diagonally across the slates, as may be desired.

Also, in the combination of the carriage carrying the adjustable disk, in which spring-bearings are arranged with the tools.

Also, in the application of stops, to arrest the motion of the slate or tool, whenever desired, so that certain kinds of lines may be stopped before they reach the end of the slate, if so desired.

A, in the drawing, represents a stationary frame, made of wood, iron, or other suitable material, and having two parallel ways or rails, B B, upon which a carriage, C, can be made to slide.

The sliding motion of the carriage can be produced by hand, or other suitable mechanism, and can be arrested by means of stops a a, which are arranged upon the rails B B, as shown, and which can be adjusted on the same by means of set-screws b b.

In the carriage C is arranged a disk, D, which fits into a perforation in the top of the carriage, and which can be turned at will, and clamped in any desired position, by means of a spring-catch, e, fitting into a perforation of the disk, as is shown more particularly in fig. 4.

In the disk is a rectangular or other perforation, as shown in figs. 1, 2, and 3, of such size as to allow the slate to pass through it.

The slate to be ruled is placed upon spring-supports, d d, which are suspended from the disk D, and the slate has thus an elastic support, which allows it to be adjusted up and down at will.

Under the carriage C is fitted, upon the frame A, a bar, block, or head, E, in which a series of ruling-tools, F F, is clamped or set. The tools are secured in the heads, the required distance apart, and the head is fixed in the desired direction upon the frame.

Thus, in fig. 1, the head is set at right angles to the line of motion of the carriage, and its tools are set as far apart as it is desired to have the lines apart on the slate.

The points or tools F are flat steel or other plates, ground to a point on one edge, as in fig. 5, and are fitted into the head E, in any suitable manner, although I prefer to have them clamped between two longitudinal parts of the head, with a piece of rubber, e, in front. The head may have slots to receive the shanks of the tools.

The tools incline somewhat towards the rear, as in fig. 4, and are set with their faces always at right angles to the line of motion, so that they may yield to the moving slate, while if they were set with their edge in front, or oblique, they would be liable to be bent aside by inequalities in the surface of the slate, and crooked lines would thus be produced.

There should be a different head, E, with its own set of tools, F, for each set of lines to be drawn, so that for horizontal lines the head would be as in fig. 1; for vertical lines, as in fig. 2, in which latter the tools are set a different distance apart; for diagonal lines, as in fig. 3, in which the tools are set at the required angle to the face of the head.

The disk D is turned in the carriage until the slate in it stands at the required angle to the line of motion; as, for example, in fig. 2, the disk is at right angles to its position in fig. 1, so that when the carriage is moved on the rails, vertical lines will be produced, while in fig. 1, horizontal lines will be marked.

In fig. 3, the disk is in still another position for the production of diagonal lines.

The angle of the diagonal lines may be varied at will, and for each different angle there should be another head, with tools, and a separate position of the disk and head.

In operating, the slate is held down upon the teeth by the aid of a presser or pad, G, fig. 4. The heads are placed at the same angles to the line of motion as is the disk, for the different sets of lines. Thus, for vertical and horizontal lines, the heads are at right angles to the line of motion, and for oblique lines, the heads are at the same angle to the line of motion as is the side of the disk-perforation corresponding to the top and bottom of the slate, as will be understood by reference to figs. 1 and 3.

Having thus described my invention, what I claim as new, and desire to secure by Letters Patent, is—

1. Inserting the marking-tools F in their heads, at

such an angle that their broad faces shall stand at right angles to the line of motion, whereby oblique rulings are produced without changing the motion of the carriage, as herein shown and described.

2. The carriage C, carrying the adjustable disk D, in which the spring-bearings *d d* are arranged, in combination with the tools F F, fitted in one head, substantially as set forth.

3. The adjustable stops *a*, in combination with the sliding carriage C, turning disk D, and tool-head E, all made and operating substantially as herein shown and described.

JOHN H. FRENCH.
